(57) **CLAIM**

The ornamental design for a file organizer, as shown and described.

DESCRIPTION

FIG. 1 is a first perspective view of a file organizer showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1; and,

FIG. 9 is a perspective view of the state when the file organizer is opened thereof.

The broken lines in the drawings depict portions of the file organizer that form no part of the claimed design.

1 Claim, 9 Drawing Sheets
